FIG. 1 is a front perspective view of a wide angled reflector unit for a spoked wheel showing our design;

FIG. 2 is an elevational view thereof taken from the front as viewed in FIG. 1;

FIG. 3 is a top plan view thereof;

FIG. 4 is an elevational view taken from the rear as viewed in FIG. 1;

FIG. 5 is a bottom plan view thereof;

FIG. 6 is a side elevational view thereof;

FIG. 7 is a cross-sectional view taken on line 7—7 of FIG. 4; and

FIG. 8 is a cross-sectional view taken on line 8—8 of FIG. 4.

The faceting is partially shown for convenience of illustration, it being understood that the faceting is continuous over the areas indicated.

We claim:

The ornamental design for a wide angled reflector unit for a spoked wheel, as shown and described.
